Specification for Design.

Patented July 6, 1920.

Application filed April 24, 1920. Serial No. 376,420. Term of patent 14 years.

To all whom it may concern:

Be it known that I, MYRON D. SALISBURY, a citizen of the United States, residing at East Orange, in the county of Essex and State of New Jersey, have invented a new, original, and ornamental Design for an Emblem, Medal, Badge, Insignia, or an Article of a Similar Nature, of which the following is a specification, reference being had to the accompanying drawing, forming a part thereof.

Figure 1 is a front elevation; and Fig. 2 is a rear elevation of an emblem, medal, badge, insignia or an article of a similar nature showing my new design.

I claim:

The ornamental design for an emblem, medal, badge, insignia, or an article of a similar nature as shown.

MYRON D. SALISBURY.
